Atty.

UNITED STATES PATENT OFFICE.

JOSEPH SILVERSTEIN, OF PEORIA, ILLINOIS.

DESIGN FOR A VEHICLE-BODY.

54,870.

Specification for Design. Patented Apr. 13, 1920.

Application filed July 3, 1919. Serial No. 308,678. Term of patent 3½ years.

To all whom it may concern:

Be it known that I, JOSEPH SILVERSTEIN, citizen of the United States, residing at Peoria, in the county of Peoria and State of Illinois, have invented a certain new, original, and ornamental Design for a Vehicle-Body, as shown in the accompanying drawing.

Figure 1 of the drawing shows a side elevation of the vehicle body.

Fig. 2 is a plan of the same.

Fig. 3 shows the vehicle body in perspective, and

Fig. 4 is a front elevation of the body, and

Fig. 5 shows the vehicle body in perspective.

I claim:

The ornamental design for a vehicle body as shown.

In testimony whereof I affix my signature in presence of two witnesses.

JOSEPH SILVERSTEIN.

Witnesses:

ROSCOE HERGET,
L. M. THURLOW.
